UNITED STATES PATENT OFFICE.

CLARK ORR, OF FORT WAYNE, INDIANA, ASSIGNOR TO GENERAL ELECTRIC COMPANY,
A CORPORATION OF NEW YORK.

REFRIGERATING MACHINE.

Application filed December 16, 1924. Serial No. 756,336.

My invention relates to refrigerating machines and more particularly to that type of machine wherein a suitable refrigerant is passed through a cycle which consists first, in compressing it while in gaseous condition; second, cooling it until it is liquefied, and third, allowing it to evaporate and expand whereby it absorbs heat and the surrounding objects are maintained at the desired low temperature.

The object of my invention is a novel construction and arrangement of parts, whereby the cooling of the refrigerant in the second step of the cycle above set forth is obtained in a simple manner without the use of water cooling. To this end I arrange a condenser, of any suitable form, such as a coil of pipe, about the machine in spaced relation thereto which produces adequate circulation of cooling air for the condenser.

Other features of novelty which characterize my invention are pointed out with particularity in the claims annexed to and forming a part of this specification. For a better understanding of my invention, reference may be had to the following description taken in connection with the accompanying drawing, in which Fig. 1 is a view, partly in section, of a refrigerating machine embodying my invention, Fig. 2 is a sectional view taken on the line 2-2 of Fig. 1, and Fig. 3 is a sectional view taken on the line 3-3 of Fig. 1.

Referring to Fig. 1 of the drawing, I have shown my refrigerating machine mounted on a cover 4 for the top of a refrigerator. The refrigerating machine comprises a base 5, a casing 6 mounted on the base and provided with a chamber 7 for containing condensed refrigerant and a compression chamber 8 containing a compressor. A motor 9 for driving the compressor is located above the compression chamber and the motor and compressor are substantially coaxial with the casing. A condenser of any suitable form may be provided for condensing the compressed refrigerant. In the present construction I have shown a coil of pipe 10, which is arranged about the casing 6 in such relation thereto that the heat radiated from the casing combined with the heat radiated from the condenser causes sufficient upward flow of air by natural draft to cool the machine during its operation. The coil of pipe 55 and the casing are substantially coaxial and

close together, so that they form a symmetrical restricted passage for air. The coil of pipe 10 has its turns spaced apart and has one end 11 connected to and communicating with the compression chamber 8 and the other end 12 connected to and communicating with the chamber 7. This arrangement of the coil of pipe 10 about the casing enclosing the motor and compressor forms a passage for air extending axially of the coil of pipe between the pipe and the casing which cools them during operation of the machine. Below the chamber 7 is an evaporator 13, which communicates with the chamber 7 in order to receive the condensed refrigerant and with the compression chamber 8 for returning the vaporized refrigerant thereto. The evaporator is usually located in the refrigerator.

The compressor located in the compression chamber 8 comprises two cylinders 14, provided with trunnions 15 and 16. The trunnions 15 are journaled in a member 17, which forms the top of the chamber 7 and the bottom of the chamber 8, and the trunnions 16 are journaled in a member 18, which forms the top of compression chamber 8 and the bottom of the enclosure of the motor 9. The lower portion of the cylinders 14 are flattened and are maintained in close contact with the top of member 17 by means of springs 19. The gaseous refrigerant is conducted to the compressor cylinders through suction pipe 20, to plugs 21, through pipes 22, to openings 23 formed in the cylinder walls. In the end of the walls of cylinders 14 are snifter valves 24, which serve to permit the passage of compressed gas into the compression chamber 8. Pistons 25, mounted in the cylinders are operated by straps 26 of an eccentric 27 mounted on shaft 28 of the motor 9.

The shaft 28 is journaled in bearings 29 and 30 formed in members 17 and 18. Compression chamber 8 is adapted to contain oil preferably sufficient in quantity to submerge the cylinders 14. The upper bearing 30 is lubricated by oil splashed into cup 30' located near the upper part of the bearing housing, an oil hole being drilled through the housing to the bearing proper. Upon the upper portion of shaft 28 is mounted the rotor 31 of the electric motor, which may be of any usual type and shown in the drawing as an induction motor. There is no 110

bearing for shaft 28 above the rotor 31. Mounted on the lower end of the shaft 28 are weights 32 arranged to be thrown out by centrifugal force. These weights act on 5 a lever 33 of an equalizer valve 34 mounted in an equalizing tube 34' connected to the plugs 21. Mounted in the suction tube or pipe 20 is an automatic valve 50 of the snifter type having a flat spring 51 (see Fig. 2). The purpose of this valve is to prevent 10 hot gases from entering the evaporator when the machine has stopped and the equalizing valve 34 is open.

In the lower part of the casing 6, there 15 is formed a depression 35, which in effect constitutes a reservoir for the collection of liquid refrigerant. In the bottom of this depression is an opening 36 which is opened and closed by a valve 37. This valve is 20 controlled by a pivoted lever 38 that has mounted on the end thereof a float 39. The float 39 will be raised when a predetermined quantity of liquid refrigerant has collected 25 in the depression 35. Communicating with the opening 36 is a tube 40 which passes refrigerant to the evaporator 13.

The evaporator consists of a liquid receiving receptacle 41 and evaporator coils 42. Inlet tube 40 communicates with the receptacle at the top and extends downwardly 30 therein well below the normal level of the liquid refrigerant. Suction pipe 20 also communicates with the top of the receptacle 41 at a point well above the level of the 35 liquid refrigerant, so as not to carry back to the compressor liquid refrigerant.

The motor 9 is completely enclosed by a 40 casing 43 extending over the sides of the stator of the motor and over the top thereof, the member 18 completing the enclosure. The outside of the casing 43 is provided with heat radiating fins 44, preferably made of copper and fastened to the casing, as by 45 soldering. The portion of the casing 6 surrounding the compressor chamber 8 is similarly provided with heat radiating fins 45.

The coil of pipe 10 for condensing the 50 refrigerant consists of finned copper tubing arranged around the casing enclosing the motor and the casing enclosing the compression chamber and outside of the fins 44 and 45. The tubing is held in place by brackets 46 and spacing members 47, between which the pipe is clamped, screws 48 holding the 55 spacing member and bracket together. The bracket is fastened to the base 5 by screws 49. The upper end 11 of the coil of pipe extends vertically downward through the fins 44 and enters the top of the compression chamber 8. The lower end 12 of the coil of pipe enters chamber 7 at a point just 60 above the depression 35 therein.

The operation of the refrigerating machine is as follows:

65 The refrigerant, such for example as sul-

phur dioxide, SO_2 , in gaseous condition is drawn through suction pipes 20 to plugs 21 through pipes 22 into the cylinder 14 through the openings 23 in the cylinder walls. The oscillation of these cylinders by reason of the slight turning movement of 70 the piston rods, during their reciprocation, causes the openings 23 to move into and out of alignment with the ends of pipes 22. The compression cylinders are single acting. 75 The refrigerant is compressed in the cylinders and passed out through the snifter valves 24 into compression chamber 8, thence into the coil of pipe 10 where the gas is cooled by the air flowing through the passage 80 between the coil of pipe and the casing of the machine. The gas is thus liquefied and the liquid refrigerant enters the chamber 7 through the end 12 of the coil of pipe and collects in the depression or reservoir 35. 85 When a sufficient quantity of refrigerant has collected, the float 39 is raised, opening valve 37 and allowing the liquid to pass through pipe 40 into receptacle 41 and evaporating coils 42 of the evaporator. The 90 liquid refrigerant fills these coils 42 and a greater part of the receptacle 41 as shown in the drawing. After absorbing heat from the refrigerator, the liquid evaporates and passes back into the refrigerating machine 95 through pipe 20.

In order to prevent oil from draining down the suction pipe 20 into the evaporator, the pipe 20 is connected into the side of the plug 21 above the end of pipe 22. 100 Any oil that passes the port openings 23 in the cylinders run down the tubes or pipes 22 into the plugs 21 and collects there. When sufficient oil collects to cover the end of tube 22, it is drawn into the cylinders with 105 the gaseous refrigerant.

When the machine is in operation, the 110 weights 32 are extended, moving lever 33 so as to close the valve 34, thus closing communication between the chamber 7 and the equalizing tube 34' and suction pipe 20. When the machine is shut down, however, the weights drop to the position shown in Figs. 1 and 2, moving lever 33 so as to open the valve 34 and thus open up communication between chamber 7 and equalizer tube 34'. This tube is connected to plugs 21 and therefore the opening of valve 34 equalizes the pressure between chamber 7 and suction pipe 20. Since chamber 8 and chamber 7 are connected by the coil of pipe, the pressure in the whole of the machine will be equalized when the machine is shut down. In order to prevent hot gases from going 120 into the evaporator when the machine has stopped and the equalizer valve 34 is open, the snifter valve 50 is provided. When the machine is operating the vaporized refrigerant is drawn from the evaporator, into 125 the compressor cylinders, the suction of the 130

compressor lifting the spring flap 51. When the machine has stopped and the equalizer valve 34 is open, the spring flap 51 has no difference of pressure on its two sides and 5 consequently the valve 50 is closed, preventing the gases from flowing into the evaporator.

If desired, the rate of cooling of the refrigerant may be increased by directing a 10 stream of air on the coil of pipe 10, and I aim in the appended claims to cover such a modification as well as any others, which do not depart from the spirit and scope of my invention.

15 What I claim as new and desire to secure by Letters Patent of the United States is:—

1. In a refrigerating machine, the combination with a casing provided with a compression chamber, a compressor in said compression chamber, a motor for driving said compressor, means forming a chamber for condensed refrigerant and an exposed coil of pipe extending around said casing for condensing the refrigerant, one end of said 20 coil of pipe being connected to and communicating with the compression chamber and the other end being connected to and communicating with the chamber containing the condensed refrigerant, said coil being spaced 25 from said casing whereby an upward current of cooling air is induced between the casing and the coil.

2. In an air-cooled refrigerating machine, the combination with a casing provided 30 with a compression chamber, a compressor arranged to discharge into said compression chamber, a motor for driving said compressor located above said compressor, and an exposed coil of pipe having heat radiating 35 projections thereon for condensing the refrigerant, means forming a chamber for condensed refrigerant, one end of said coil of pipe being connected to and communicating with the upper portion of the compression chamber and the other end being connected to and communicating with the chamber for containing the condensed refrigerant, an evaporator below said chamber for containing said condensed refrigerant, said evaporator 40 communicating with said last mentioned chamber in order to receive the condensed refrigerant, said evaporator also communicating with said compression chamber for returning the vaporized refrigerant thereto.

45 3. In an air-cooled refrigerating machine, the combination with a casing provided with a compression chamber, the outer wall of said compression chamber having heat radiating projections thereon, a compressor within said compression chamber, a motor for driving said compressor, and an exposed coil

of pipe for condensing the refrigerant, means forming a chamber for condensed refrigerant, said coil of pipe surrounding said casing and said projections, one end of said coil of pipe being connected to and communicating with the upper portion of said compression chamber and the other end being connected to and communicating with the chamber for condensed refrigerant, said coil of pipe being so spaced from said casing as 70 to form a passage for the flow of air between the casing and the coil.

4. In an air-cooled refrigerating machine, the combination with a casing having outwardly projecting heat radiating fins thereon and provided with a compression chamber, a compressor within said compression chamber, a motor for driving said compressor, said motor being located above said compressor and a coil of pipe for condensing 80 the refrigerant, means forming a chamber for condensed refrigerant, said coil of pipe surrounding and spaced from said casing and said fins, said coil of pipe being so spaced from said casing as to form a passage 85 for the flow of air between the casing and the coil, one end of said coil of pipe being connected to and communicating with the upper portion of said compression chamber and the other end being connected to and communicating with the condenser chamber, an evaporator below said chamber for containing 90 said condensed refrigerant, said evaporator communicating with said last mentioned chamber in order to receive the condensed 95 refrigerant, said evaporator also communicating with said compression chamber for returning the vaporized refrigerant thereto.

5. In a refrigerating machine, the combination with a casing provided with a compression chamber, a compressor within said compression chamber, a motor within said casing for operating the compressor, said motor being located above said compressor, radiating fins on the portions of said casing 100 that enclose said compressor and said motor, and a coil of pipe for condensing the refrigerant, means forming a chamber for condensed refrigerant, said coil of pipe surrounding said casing outside of said fins, one 105 end of said coil of pipe being connected to and communicating with the compression chamber and the other end being connected to and communicating with the chamber for containing the condensed refrigerant.

6. In a refrigerating machine, the combination with a casing provided with a compression chamber, a compressor within said compression chamber, a motor within said casing for operating the compressor, said motor being located above said compressor, radiating fins on the portions of said casing 110 that enclose said compressor and said motor, and a coil of pipe for condensing the refrigerant, means forming a chamber for condensing the refrigerant, 115

densed refrigerant, said coil of pipe surrounding said casing outside of said fins, one end of said coil of pipe being connected to and communicating with the upper portion 5 of the compression chamber and the other end being connected to and communicating with the chamber for containing the condensed refrigerant.

7. In a refrigerating machine, the combination with a casing provided with a compression chamber, a compressor within said compression chamber, a motor within said casing for operating the compressor, said motor being located above said compressor, 10 radiating fins on the portions of said casing that enclose said compressor and said motor and a coil of pipe for condensing the refrigerant, means forming a chamber for condensed refrigerant said coil of pipe surrounding said casing outside of said fins, one end of said coil of pipe being connected to and communicating with the upper portion 15 of the compression chamber and the other end being connected to and communicating with the chamber for containing the condensed refrigerant, an evaporator below said chamber for containing said condensed refrigerant, said evaporator communicating with said last mentioned chamber in order to 20 receive the condensed refrigerant, said evaporator also communicating with said compression chamber for returning the vaporized refrigerant thereto.

8. In a refrigerating machine, the combination with a casing provided with a compression chamber, a compressor having a cylinder within said compression chamber, means forming a chamber for condensed refrigerant, a condenser communicating 35 with said compressor and said chamber for condensed refrigerant, a motor for driving said compressor, the cylinder of said compressor having a downwardly extending intake opening, a plug communicating with said opening, a pipe extending downward from said opening into said plug, and a suction pipe connected into the side of said plug and above the end of said first mentioned pipe for conveying vaporized refrigerant to said compressor.

9. In a refrigerating machine, the combination with a casing provided with a compression chamber, a compressor in said compression chamber, means forming a 40 chamber for condensed refrigerant, a condenser communicating with said compressor and said chamber for condensed refrigerant, an evaporator, said evaporator communicating with the chamber containing the condensed refrigerant in order to receive the condensed refrigerant, a suction pipe connecting said evaporator to said compression chamber for returning the vaporized refrigerant thereto, an equalizing valve connected to said suction pipe for equalizing

the pressure between the chamber containing the condensed refrigerant and the suction pipe when said machine stops, and an automatic valve in said suction pipe for preventing gases from entering the evaporator when the machine is stopped and the equalizing valve is open.

10. In a refrigerating machine, the combination with a casing provided with a compression chamber, a compressor in said compression chamber, means forming a chamber for condensed refrigerant, a condenser communicating with said compressor and said chamber for condensed refrigerant, an evaporator, said evaporator communicating with the chamber containing the condensed refrigerant in order to receive the condensed refrigerant, a suction pipe connecting said evaporator to said compression chamber for returning the vaporized refrigerant thereto, 75 an equalizing valve connected to said suction pipe, centrifugal means for closing said valve and for opening the same when the machine stops to equalize the pressure between the chamber containing the condensed refrigerant and said suction pipe, and an automatic valve in said suction pipe for preventing gases from entering the evaporator when the machine is stopped and said equalizing valve is open.

11. In an air-cooled refrigerating machine, the combination of a casing comprising a compression chamber having a compressor therein, and a chamber having an electric motor therein for driving said compressor, an evaporator, and a condenser surrounding and spaced from said casing, said condenser being connected at one end with said compression chamber and at the other end with said evaporator, said condenser and said 100 casing being cooled jointly by a common current of air induced therebetween.

12. In a refrigerating machine, the combination of a casing comprising a compression chamber, a compressor in said chamber, 105 lateral heat radiating projections on said casing, and a condensing coil surrounding said casing, said condensing coil being so spaced from said casing as to induce an upward current of cooling air between the 110 casing and the coil sufficient to cool the condensing coil during operation of the machine.

13. In an air-cooled refrigerating machine, the combination of a casing comprising a compression chamber, a compressor in said chamber, said casing comprising a second chamber, an electric motor for driving said compressor entirely enclosed by said second chamber, a condensing coil surrounding said casing and connected to said compression chamber, said casing having a series of heat radiating fins arranged opposite said motor and having a series of heat radiating fins arranged opposite said compressor.

14. A refrigerating machine comprising means forming a chamber for condensed refrigerant and a compression chamber, a compressor in said compression chamber and an air-cooled condenser coil having one end connected with the compression chamber and the other end connected with the chamber for condensed refrigerant, said condenser coil surrounding said compression chamber, said condenser being so spaced from said compression chamber as to induce an upward current of air in the space between the coil and the chamber which cools the condenser and the machine.
15. A refrigerating machine comprising a casing forming a compression chamber, a compressor in said chamber, a motor connected to drive said compressor and arranged in said casing, outwardly projecting fins on said casing, and an air-cooled condenser comprising a coil of pipe surrounding said casing in spaced relation therewith, said condenser being so spaced from said casing as to induce an air current over said fins in the space between the casing and the coil.
16. An air-cooled refrigerating machine comprising a casing forming a compression chamber, a compressor therein, an electric motor in said casing having a driving connection with said compressor, and a condenser surrounding and spaced from said casing in such relation as to induce a flow of air therebetween by natural draft so that said condenser and said casing are cooled jointly by a common current of air induced therebetween.
17. In a refrigerating machine, the combination of a casing having a compressor therein, a motor for driving said compressor, and a condenser surrounding said casing in such relation thereto as to form an air
- passage between said casing and said condenser and to induce sufficient flow of air by natural draft to cool said casing and condenser during operation of the machine.
18. In a refrigerating machine, the combination of a casing having a compressor therein, a motor for driving said compressor, and a condenser in the form of a coil of pipe surrounding said casing in such relation thereto as to form an air passage between the same and said casing and to induce sufficient flow of air by natural draft to cool said casing and condenser during operation of the machine.
19. In a refrigerating machine, the combination of a casing having a compressor therein, a motor for driving said compressor, and a condenser in the form of a coil of pipe having its turns spaced apart and surrounding said casing in such relation thereto as to form an air passage between the same and said casing and to induce sufficient flow of air by natural draft to cool said casing and condenser during operation of the machine.
20. In a refrigerating machine, the combination of a compression heat radiating casing containing compressed refrigerant, a refrigerant compressor arranged in said casing and discharging into the same, a motor arranged to drive said compressor, and a condenser surrounding said casing in such relation thereto as to form an air passage between said casing and said condenser and to induce sufficient flow of air through said passage by natural draft to cool said casing and condenser during operation of the machine.

In witness whereof, I have hereunto set my hand this 9th day of Dec., 1924.

CLARK ORR.
